(57) CLAIM

The ornamental design for a hijab as shown and described.

DESCRIPTION

FIG. 1 is a right side front perspective view of a hijab showing my new design;

FIG. 2 is a front view thereof;

FIG. 3 is a left side front perspective view thereof;

FIG. 4 is a left side view thereof;

FIG. 5 is a left side rear perspective view thereof;

FIG. 6 is a rear view thereof;

FIG. 7 is a right side rear perspective view thereof; and,

FIG. 8 is a right side view thereof.

The broken lines depicting the button and buckle elements represent portions of the hijab that form no part of the claimed design.
